UNITED STATES PATENT OFFICE

2,617,427

SMOKING DEVICE

George W. Rehfeld, Manhattan, Kans.

Application February 13, 1950, Serial No. 143,995

7 Claims. (Cl. 131—191)

1

This invention relates to a device for smoking tobacco in loose form, and particularly to a device of this character simulating a cigarette or cigar holder, the present application being a continuation in part of my co-pending applications, Ser. No. 577,814, filed February 14, 1945, now Patent 2,546,237, and Ser. No. 618,144, filed September 24, 1945, now abandoned.

The principal objects of the invention are to provide a smoking device of small, compact construction; to provide a smoking device having a substantially cylindrical shaped receptacle and a reciprocable stem for compacting the tobacco in the receptacle and for pushing the tobacco forwardly therein and to discharge the ashes and accumulated matter subsequent to each use of the device; to provide a smoking device having a tobacco receptacle formed essentially of light weight material composed of spaced apart members interconnected by an insulating covering so as to prevent conduction of heat to the stem to facilitate handling of the device without danger of burning the fingers; and to provide the stem with a chamber for containing a filtering material through which the smoke is drawn.

Further objects of the invention are to provide a cool smoking device that is sanitary and pleasant to smoke; to provide a smoking device which prevents discharge of tobacco from the receptacle when using loose tobacco; to provide a smoking device that is adjustable for containing various amounts of tobacco; to provide a smoking device that is easily disassembled and cleaned; and to provide a smoking device wherein the tobacco may be tamped to enhance the burning quality thereof.

In accomplishing these and other objects of the invention as hereinafter pointed out I have provided improved structure, the preferred forms of which are illustrated in the accompanying drawings wherein:

Fig. 1 is a perspective view of a smoking device constructed in accordance with the present invention.

Fig. 2 is a similar view illustrating the tobacco receptacle as formed with a series of spaced rings connected together by an insulating sheath or covering.

Fig. 3 is a longitudinal section through the smoking device.

Fig. 4 is a similar section showing the filter chamber of the stem charged with tobacco and a charge of burning tobacco within the smoking receptacle.

Fig. 5 is a cross section of the line 5—5 of Fig. 4.

Fig. 6 is a perspective view of a smoking de-

2

vice equipped with a modified form of cage for the tobacco receptacle.

Fig. 7 is a longitudinal section through the form of invention shown in Fig. 6.

Fig. 8 is a perspective view of a further modified form of the invention.

Fig. 9 is a longitudinal section through the form of invention shown in Fig. 8.

Referring more in detail to the drawings:

10 1 designates a smoking device embodying the features of the present invention and which includes a substantially elongated cylindrical receptacle or chamber 2 and stem 3. The member 2 is preferably of composite construction in that it is composed of a series of substantially ring shaped members 4, 5, 6, 7, and 8, which are preferably formed of a light weight material such as, for example, an aluminum alloy. The members 4 to 8 each include substantially cylindrical wall portions 9 having substantially equal inner diameters to form a continuous bore or tobacco receiving space 10. The outer end member 8 is of somewhat longer length than the intermediate ring members 5, 6, and 7, to provide a cage portion 11, which may be formed integrally therewith and have a circular series of openings 12 conforming in shape with a plane geometrical figure having greater length than width with the adjacent long sides being sufficiently close to each other to define substantially long narrow bars 13 extending substantially parallel to the longitudinal axis of the cylindrical end member 8. In the drawings the openings 12 are shown of substantially rectangular shape, with the longer dimensions thereof extending in the direction of axis of the receptacle. Intermediate the openings are the relatively narrow bar portions 13 connecting an annular outer rim 14 with the body portion 15 as best shown in Figs. 2 and 3.

40 15 The member 4 includes a tapered tube 16 to form an internal tapering seat 17 encircling the reduced open end 18 of the member.

In assembling the ring members in concentric axial alignment, and with spaces 19 therebetween the ring members may be assembled on a mandrel, not shown. The ring members are then wrapped with a fabric material 20 impregnated with a heat resistant adhesive and which is of sufficient length to lap the outermost ring members 4 and 8. The fabric is also of a length so as to provide one or more laps about the receptacle. After application of the fabric 20, an insulating covering 21, for example leather, is coated on the innerface 22 thereof, with the adhesive material and wrapped over the fabric with the edges 23 and 24 thereof overlapped and sealed together so as to form a

substantially smooth continuous insulating sheath which retains the rings in spaced assembly and provides a finger hold that is kept in relatively cool condition. After the adhesive is set, the completed receptacle is removed from the mandrel to provide, in effect, a continuous bore. The ring members are thus retained in spaced relation so as to prevent direct conduction of heat from the cage member to the member 4 having the tapering seat portion with which the stem is engaged as later described. The stem 3 may also be formed of metal and has an elongated tubular portion 25 and a tapering head 26 joins with the tubular portion of the stem by a shoulder 27.

The head 26 has a tapered exterior face 28 corresponding with the tapering seat 17 so that it tightly wedges therein and forms a leak tight seal between the stem and the receptacle when the stem is retracted in the receptacle as illustrated in Fig. 3. The stem is preferably formed of relatively thin material, and in the illustrated instance, the head portion 26 is reinforced by a conical insert 29 having its outer end 30 registering with the end 31 to provide a tamping face which cooperates with tobacco that is loaded in the stem to effect compacting the tobacco within the forward end of the receptacle without packing the tobacco too tightly within the stem. The head 26 fits rather tightly within the inner diameter of the ring members 5, 6, 7, and 8, and therefore it may be desirable to slightly bevel the rear edges of the ring members as indicated 32 to facilitate movement of the head of the stem thereacross. The outer end of the stem has a reduced neck 33 for connecting a bit 34.

In using the smoking device just described the stem is drawn retractively within the receptacle until the head 26 thereon wedges within the tapered seat 17. The smoking device is then filled with tobacco by using the device as a scoop in the tobacco so that the tobacco fills the stem and receptacle. The finger is then placed in the open end of the cage, and the stem is reciprocated within the receptacle to pack the tobacco between the finger and the head 26 of the stem. When the tobacco is sufficiently packed the face of the charge is substantially level with the innermost edges of the openings 12 in the cage 11. Upon withdrawal of the stem to wedge the head 26 within the tapered seat 17 a space 35 (Fig. 5) is established between the packed tobacco and the tobacco within the stem. The packed tobacco is then lighted and sufficient puffs are made through the stem to establish good burning of the tobacco, the body of packed tobacco is then shifted into the cage by moving the stem forwardly within the receptacle until the burning face of tobacco is substantially even with the open end of the cage. Smoking can then continue until the tobacco is completely burned. The tobacco within the stem serves as a filter to remove nicotine. The long travel of the smoke through relatively large space 35 and the filter assure a cool smoke. The formation of the receptacle prevents heat of the burning tobacco from being conducted to the stem, consequently the bit and stem remain in cool condition. After the smoke the ashes may be shaken from the cage of the receptacle by tapping the receptacle on a suitable surface or the burning tobacco may be ejected by the use of the stem. During burning of the packed tobacco the particles become sufficiently united or fused together so that the ashes remain within the cage until the entire mass has been ejected.

The form of the invention shown in Figs. 6 and 75

7 is substantially the same as the form just described with the exception that the bar portions 36 of the cage 37 are bulged outwardly to allow slight expansion of the packed tobacco therein to assist in retaining the tobacco.

In the form of the invention illustrated in Figs. 8 and 9 the stem 38 and bit 39 are of the same construction as in the first described form of the invention, but the tapered member 40 of the receptacle 41 and cage 42 are interconnected by a preformed heat resistant sleeve 43 composed of fiber or the like. In this form the members 41 and 42 are pressed into the open ends of the sleeve and if required, may be cemented thereto by a heat resistant adhesive as in the attachment of insulating covering in the first described form of the invention. To facilitate movement of the head of the stem the inner edges of the members 41 and 42 are beveled as indicated at 44 and 45. Otherwise the construction and operation is similar to the other forms of invention.

It is obvious that the smoking device comprises a mouthpiece 34, stem 3 and tobacco receiving chamber 2 wherein all the parts are in axial alignment and in interconnected relation, and that the tobacco chamber 2 includes the ring 8 which forms an end member of metal of cylindrical form, completely open at both ends, and that it is provided intermediate its ends with a series of parallel substantially rectangular openings 12 so that the adjacent walls of the openings define the long narrow bars 13 and the opposite ends of the openings define the sections of annular walls of different widths, the wall of greatest width being secured to the insulating wall of the chamber. It is further obvious that the wall of the chamber is formed of insulating material and that the end opposite the metal end member or ring 8 has the member 4 in the form of a tapered metal tube, the larger end of which is secured to the chamber. It is also obvious that the stem 3 has the tapered portion thereof slidably mounted in the tapered metal tube of the chamber to provide a tight fit therein, with the head 26 together with the insert 29 forming a wall thickness to provide a substantial piston surface at the larger end thereof and a bore of sufficient size to receive loose tobacco therein, whereby manipulation of the stem within the chamber causes tobacco to enter said stem and provide a filter.

From the foregoing it is obvious that I have provided a smoking device that is of small compact construction and which is constructed for cool smoking of tobacco since the receptacle member is formed to prevent conduction of heat from the burning tobacco to the stem of the device. The relatively large smoke passage and filter also assure cool smoke that is free from oils and most of the nicotine.

What I claim and desire to secure by Letters Patent is:

1. In a smoking device of the type comprising a mouthpiece, stem and tobacco receiving chamber, wherein all parts are in axial alignment and in interconnected relation, said tobacco chamber including a cylindrical wall of insulating material, an end member of metal of cylindrical form at one end thereof and completely open at both ends and provided intermediate said ends with a series of parallel substantially rectangular openings, the adjacent walls of the openings defining long narrow bars and the opposite ends of the openings defining sections of annular walls of different widths, the wall of greatest width being secured

to an end of the cylindrical wall of the tobacco chamber, the tobacco receiving chamber having at the other end a tapered metal tube the larger end of which being secured to the cylindrical wall of said chamber at said other end of the chamber, said stem having a tapered portion to be slidably mounted within the tapered metal tube to provide a tight fit therein, said stem having a wall thickness to provide a substantial piston surface at the larger end thereof and a bore area of sufficient size to receive loose tobacco therein, whereby manipulation of the stem within the chamber causes tobacco to enter said stem.

2. In a smoking device as described in claim 1 wherein said bar portions are bulged outwardly from the walls of the end member to facilitate in retaining tobacco within said chamber.

3. In a smoking device of the type comprising a mouthpiece, stem and tobacco receiving chamber wherein all parts are in axial alignment and in interconnected relation, said tobacco chamber including a cylindrical wall of insulating material, an end member of metal of cylindrical form and completely open at both ends and provided intermediate said ends with a series of parallel elongated openings defining narrow bars and the opposite ends of the openings defining sections of walls of different widths, the wall of greater width being secured to an end of the cylindrical wall of the tobacco chamber, and a metal coupling connected with the other end of the tobacco receiving chamber and slidably connecting the stem with the tobacco receiving chamber for reciprocation of the stem within said chamber.

4. In a smoking device of the type comprising a cylindrical tobacco receiving chamber and a stem in axial alignment with said chamber, said tobacco receiving chamber including an end member of metal of cylindrical form and completely open at both ends and provided intermediate said ends with a series of parallel elongated openings defining narrow bar portions therebetween and the opposite ends of the openings defining sections of annular walls of different widths, a metal coupling member spaced axially from the wall of greater width, at least one metal ring between and spaced from the end and coupling members, and a sheath of insulating material encircling the ring and connected at one end with the wall of the end member of greater width and at the other with the metal coupling member, whereby the stem is reciprocable within the tobacco chamber.

5. In a smoking device of the type comprising a cylindrical tobacco receiving chamber and a stem in axial alignment with said chamber, said tobacco receiving chamber including an end member of metal of cylindrical form and completely open at both ends and provided intermediate said ends with a series of parallel elongated openings defining narrow bar portions therebetween and the opposite ends of the openings defining sections of annular walls of different widths, a metal coupling member spaced axially from the wall of greater width, at least one metal ring between and spaced from the end and coupling members, an adhesive impregnated fabric encircling the ring member and connected with the wall of the end member of greater width and with the coupling member, and a sheath of insulating material encircling the fabric and connected therewith by said adhesive, said stem being slidably connected to the tobacco receiving

chamber by the coupling member for reciprocation in said chamber.

6. In a smoking device of the type comprising a mouthpiece, stem and tobacco receiving chamber, wherein all parts are in axial alignment and in interconnected relation, said tobacco chamber including a cylindrical wall formed of insulating material, an end member of metal of cylindrical form and having openings in the side wall thereof and exposed to atmosphere, said end member being completely open at both ends and connected with one end of the cylindrical wall of the tobacco receiving chamber, the cylindrical wall of the tobacco receiving chamber having at the other end a tapered metal tube the larger end of which is secured to said chamber at said other end, said stem having a tapered portion to be movably mounted within the tapered metal tube, said larger end of the tapered metal tube and said tapered portion of the stem being of relative size and shape for the tapered portion of the stem to be retracted into the tube to provide a tight fit therein, and the tobacco chamber extending the full length of said insulating cylindrical wall and from the larger end of the tapered metal tube to the end member, said stem having a wall thickness to provide a substantial piston surface at the larger end thereof and a bore area of sufficient size to receive loose tobacco therein, whereby manipulation of the stem within the chamber causes tobacco to enter said stem.

7. In a smoking device of the type comprising a mouthpiece, stem and tobacco receiving chamber wherein all parts are in axial alignment and in interconnected relation, said tobacco chamber including a cylindrical wall of insulating material, an end member of metal of cylindrical form and completely open at both ends and provided intermediate said ends with a series of openings conforming in shape with a plane geometrical figure having a greater length than width with the adjacent long sides being sufficiently close to each other to define long, narrow bars extending substantially parallel to the longitudinal axis of the cylindrical end member, and said opposite ends of the openings defining sections of walls of different widths, the wall of greater width being secured to an end of the cylindrical wall of the tobacco chamber, and a metal coupling member connected with the other end of the tobacco receiving chamber and slidably connecting the stem with the tobacco receiving chamber for reciprocation of the stem within said chamber.
